<img alt="Technical drawings of a mechanical device, likely a track or rail system, with various components labeled with numbers. The drawings include Fig. 3, Fig. 7, Fig. 10, Fig. 4, Fig. 11, and Fig. 12. The drawings show a central vertical support with horizontal beams and various mechanical parts like wheels and brackets. Labels include 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 661, 662, 663, 664, 665, 666, 667, 668, 669, 670, 671, 672, 673, 674, 675, 676, 677, 678, 679, 680, 681, 682, 683, 684, 685, 686, 687, 688, 689, UNITED STATES PATENT OFFICE.

CHARLES A. CARMANY, OF SCHAEFFERTOWN, PENNSYLVANIA.

MUSIC STAND.

Application filed April 11, 1922. Serial No. 551,444.

To all whom it may concern:

Be it known that I, CHARLES A. CARMANY, a citizen of the United States, residing in Schaefferstown, Lebanon County, Pennsylvania, have invented certain Improvements in Music Stands, of which the following is a specification.

My invention relates to certain improvements in music stands for which patent was granted to me on the 16th day of September, 1919, No. 1,316,424.

The object of my invention is to improve the detail construction of the stand and the means for retaining the music on the stand and the frictional mechanism for holding the parts in the position to which they are adjusted.

In the accompanying drawings:

Fig. 1 is a front view of my improved music stand, showing the music-carrying section extended to its full height;

Fig. 2 is a side view;

Fig. 3 is an inverted sectional plan view on the line 3—3, Fig. 1;

Fig. 4 is an inverted sectional plan view on the line 4—4, Fig. 1;

Fig. 5 is an enlarged sectional elevation on the line 5—5, Fig. 1;

Fig. 6 is a sectional view on the line 6—6, Fig. 5;

Fig. 7 is an enlarged sectional view on the line 7—7, Fig. 1;

Fig. 8 is a rear view of a portion of Fig. 7;

Fig. 9 is a sectional view on the line 9—9, Fig. 8;

Fig. 10 is a sectional view on the line 10—10, Fig. 1;

Fig. 11 is a sectional view on the line 11—11, Fig. 10;

Fig. 12 is a perspective view of the lower portion of the supporting bar;

Fig. 13 is a perspective view of a portion of the lower rail;

Fig. 14 is a perspective view of the clamping plate for the lower rail;

Fig. 15 is a view of a modification of the means for frictionally holding the upper rail to the flat supporting bar;

Fig. 16 is a sectional view on the line 16—16, Fig. 15;

Fig. 17 is a view of another modification of the means for frictionally holding the upper rail to the flat supporting bar; and

Fig. 18 is a sectional view on the line 18—18, Fig. 17.

Referring to the drawings, 1 is a spindle,

which supports the stand. This spindle is bent at its lower end 2 to form an eye through which passes a bolt 3 having a thumb nut 4 thereon. This bolt also passes through the forked end of a shank 5, which is adapted to a socket in the end of the upper portion 6 of the base of the stand. Secured to the spindle is a collar 7 having laterally extended portions 8. Mounted on the spindle, above the collar, is a flat supporting bar 9. This bar is bent at the lower end 10 so as to provide a flat bearing, which is in contact with the laterally extended portions 8 and has a flange 11, which rests back of the portions 8 so as to hold the bar from turning. The upper end of the flat supporting bar is bent at 12 and is perforated for the passage of the spindle. The spindle has a ring 13 at its outer end adapted to a groove which limits the movement of the flat supporting bar. The bar has sufficient movement to allow it to be raised and turned on the spindle.

In order to secure the lower rail 14, which is angular in shape, as shown in Fig. 5, to the flat supporting bar 9, the rail is perforated at 15. Adjustably mounted on the flat supporting bar is a plate 16 having ears 17, which are bent around the edge of the plate so that, while the plate can slide on the bar, it is held laterally in position. The plate is cut at the upper end to form a tongue 18, which bears frictionally upon the bar. The plate has a tapered end 19. On the bar are two pins 20, which extends through the holes 15 in the lower rail 14 and, when the plate 16 is pushed down over the upturned portion of the rail 14, it comes in contact with the pins 20. This construction rigidly holds the lower rail 14 to the supporting bar and, yet, by sliding the plate 16 on the bar, the rail can be easily detached.

21 is the upper rail, which is arranged to slide on the supporting bar to accommodate music books, or sheets of music, of different heights. A plate 22, Fig. 6, is secured to the upper rail 21 by rivets 23. This plate has inturned ears 24, which pass around the edges of the bar 9 and form guides for the plate. A tongue 25 is cut from the plate 22, as shown in Fig. 6, and acts as a means for frictionally holding the upper rail to the flat bar, as illustrated in Fig. 5, so that, when the upper rail is adjusted on the bar, the tongue retains the rail in the position in which it is adjusted. Pivoted to each end of the lower rail 14 are links 26 and pivoted

to the ends of the upper rail are links 27. Each lower link 26 is pivoted at 28 and extending through the perforation is a rivet 29. A plate 30 is pivoted to the link 26 by the rivet 29. The perforation 28 in the link 26 is countersunk and the plate 30 is shaped to fit this countersunk portion and is also countersunk to receive the beveled head of the rivet 29, Fig. 7. The plate has turned flanges 31, at each edge. These flanges form a slideway for the upper link 27.

In order to hold the plate frictionally to the link 26, a spring plate 32 is provided through which the rivet extends and the ends of this spring plate bear against the link. In order to prevent the plate from turning, the end of the plate is bent at 33 and extends into an opening 34 in the link, Figs. 7, 8 and 9. Stops 35 are formed on the link 27. These stops limit the movement of the two links. The lower end of the upper link is bifurcated, forming arms, which are bent out, as shown at 36, to form finger holds by which the upper rail can be adjusted in position.

The construction hereinbefore described allows the upper rail to be moved towards and from the rail having the link portions. When it is desired to extend the movement, the links can be turned on their pivots, as shown by dotted lines in Fig. 1. This arrangement also allows the links to aid in supporting the music.

In order to secure the music to the lower rail, a series of clamps 37 is pivoted to the lower rail, as illustrated in Figs. 1, 10 and 11. The clamps have lateral projections 38, which rest in sockets 39 in the horizontal portion of the lower rail 14. Bearing against each clamp is a flat spring 40, the ends of which are located in sockets 41 pressed out from the rail 14. Each clamp 37 has a tongue 42, which is in contact with the spring 40 so that the spring will hold the clamp 37 in the position shown by full lines, Fig. 10, or that shown by dotted lines in said figure. The clamps may be spaced apart, as desired.

Each spring 40 has a projection 43 at each edge, which tends to retain the clamps in place. In the present instance, four clamps are shown.

Pivoted at 44 to the upper rail at each end is an arm 45 made of sheet metal, in the present instance, and having a portion bent to form a channel into which extends the horizontal portion of the upper rail when the arms are down, as indicated in Fig. 3. Carried by the arms are springs 46, which bear upon the upper edges of the sheets of music. The arms, in the present instance, have slotted extensions 47, which are bent so as to allow the springs 46 to be passed through the slots and to be held frictionally

to the arms. In some instances, the means of securing the upper rail 21 to the supporting bar may be made as shown in Figs. 15 and 16, the top rail being slotted at 48 to receive the headed rivets 49, which are attached to a plate 22^a, the rivets being held in place in the slot by a spring tongue 50. The plate 22^a has a tongue 25^a, which bears against the flat bar. The upper rail may be held in place as shown in the modifications, Figs. 17 and 18.

On a plate 54 are pins 51, which extend through perforations in the upper bar 21^a in the same manner as the pins 20 extend through the perforations in the lower bar. A plate 52 slides on the supporting bar and extends over the upper rail. This plate has a spring tongue 53. The plate 54 is mounted on the supporting bar 9 and is held in place by ears 55 bent from the plate 52.

By this arrangement, the plate 54 can slide on the supporting bar and the plate 52 can slide on the plate 54. Located between the two plates 52 and 54 is a third plate 56 through which the tongue 53 extends. By sliding this plate 56, the tongue can be raised so as to allow the plate 52 to be adjusted freely.

I claim:

1. The combination in a music stand, of a supporting spindle; a flat supporting bar mounted to turn on said spindle and having means for holding it in either of its two positions; an upper and a lower rail; connecting links at the ends of the rails; and means for removably holding the rails to the bar.

2. The combination in a music stand, of a supporting spindle; a flat supporting bar; a perforated lower rail; pins on the bar extending through the perforations in the rail; and a sliding plate for removably holding the rail on the pins of the bar.

3. The combination in a music stand, of a supporting spindle; a flat supporting bar mounted on said spindle; a lower rail; means upon the bar for detachably holding the rail thereon; an upper rail; a sliding plate mounted upon said bar and attached to the upper rail; and means on said plate for frictionally holding the plate to the bar.

4. The combination in a music stand of a shank arranged to enter a socket in a base; a spindle pivotally connecting the shank to the spindle; a bolt and nut for holding the spindle in the position in which it is adjusted; a bar arranged to slide and turn on the spindle; means for holding the bar in either of its two positions; a fixed lower rail; and a movable upper rail carried by the bar.

5. The combination in a music stand, of a spindle; a flat bar bent at each end and perforated for the passage of the spindle; a collar on the spindle having a lateral ex-

tension, the lower portion of the bar having a flange engaging the extension of the collar when the bar is in either of its two positions; and a music supporting rail mounted on the bar.

6. The combination in a music stand, of a spindle; a flat supporting bar on the spindle; an angular lower rail detachably secured to the bar; spring clamps on the rail for holding the music sheets; an angular upper rail arranged to slide on said bar; means for frictionally holding the upper rail in position; arms pivoted to swing toward and from the said upper rail and to frictionally engage the same, and springs upon said arms arranged longitudinally upon said rail to retain the music sheets on the rail.

7. The combination in a music stand, of a flat bar; a lower music supporting rail removably held on the bar; an upper rail; a plate to which the upper rail is secured, said plate having inturned lugs engaging the bar; and a spring tongue on the plate resting against the bar to hold the plate and its rail frictionally in position.

8. The combination in a music stand, of a flat supporting bar; pins thereon; an angular music supporting rail perforated to receive the pins; and a sliding plate on the bar holding the rail on the pins.

9. The combination in a music stand, of a flat supporting bar; pins thereon; an angular music supporting rail perforated to receive the pins; a plate on the bar having lugs bent around the edges of the bar and having a spring tongue bearing on the bar and also having a portion extending over the rail and between the pins.

40 10. The combination in a music stand, of a supporting bar; an upper and a lower rail carried thereby; a link pivoted at each end of each rail; and a plate pivotally attached to one of the links at each side and having a slideway for the other link.

45 11. The combination in a music stand, of a supporting bar; an upper and a lower rail carried thereby; a link pivoted at each end of each rail; a plate pivotally attached to

one of the links at each side and having a 50 slideway for the other link; a countersunk rivet forming the pivot; and a spring plate attached to the rivet tending to hold the plate frictionally in place on its link.

12. The combination in a music stand, of a flat supporting bar; an upper and a lower rail on the bar; two links at each side of the stand pivotally connected to the upper rail and to the lower rail; a plate at each side in which one of the links can slide; a 60 countersunk pivot for the plate; and a spring plate engaging the pivot, and having a bearing in the link through which the pivot extends, said link being perforated to receive a bent end of the spring plate. 65

13. The combination in a music stand, of a supporting bar; a lower rail detachably secured to the bar; an upper rail arranged to slide on the bar; and links pivotally connected to the end of said rails and sliding 70 one on the other, one of said links having stops and having fingerholds at the ends.

14. The combination in a music stand, of a supporting bar; upper and lower angular music sheet supporting rails; an arm pivoted to one angular member of one of the rails to swing relative thereto and be frictionally held thereby, and a spring member carried by said arm and disposed to hold the sheet music yieldingly against the other 75 member of the rail. 80

15. The combination in a music stand, of a shank; a spindle pivoted to the shank; a flat supporting bar bent and perforated for the passage of the spindle, the lower end 85 of the bar having a flange; a collar on the spindle engaged by the flange; a perforated, angular lower rail; pins on the bar extending into the perforations; a sliding plate on the bar extending over the rail; an upper 90 rail; a plate to which the upper rail is attached, said plate being arranged to slide on the bar and to be held frictionally in position; links connected to the outer ends 95 of the rails and slidably connected together; and spring clamps on each rail.

CHARLES A. CARMANY.
